ELECTRO-OPTICAL SIGNALING

Fritz Schröter, Berlin, Germany, assignor to
Telefunken Gesellschaft für Drahtlose Tele-
graphie m. b. H., Berlin, Germany, a corpora-
tion of Germany

Application September 29, 1936, Serial No. 103,083
In Germany September 24, 1935

7 Claims. (Cl. 178—7.2)

This invention relates to electro-optical signaling and, in particular, to facsimile in television systems embodying "actino-dielectric effect" transmitters.

It is well known that certain luminescent materials have the property of changing their dielectric constant upon exposure to light and has been reported both in "Annalen der Physik" Volume 28, pages 490 et seq. for the year 1909 by Lenard, and "Der Handbuch der Experimental Physik" Volume 23, Part I by Wien and Harms, 1928, pages 213 through 245. This phenomena, known by the term "actino-dielectric effect" while definite and stable, does not lend itself readily 15 to be used in practice in view of the comparatively small change which takes place.

Accordingly, one of the objects of this invention is to provide ways and means to utilize practically the "actino-dielectric effect" of luminescent materials. This effect can be used efficaciously 20 in television and facsimile systems for transmitting various types of subject matter, and in particular, is adapted to be used wherever it is desired to convert optical phenomena into elec- 25 trical phenomena.

Accordingly, another object of my invention is to provide new ways and means of converting optical phenomena into electrical phenomena.

Another object of my invention is to provide 30 an electro-optical transmitting system which has improved properties.

Other and ancillary objects will become apparent both to the public and those skilled in the art upon a reading of the specification taken together with the drawing.

In the drawing, Fig. 1 is a schematic illustration representing one form of my invention; and

Figs. 2 and 3 show a perspective and plan 40 view of another embodiment of my invention.

In Fig. 1 a layer of luminescent material 10 is positioned between a plate electrode 11 and a coarse mesh-like electrode 12 forming a condenser in which the luminescent layer 10 serves 45 as a dielectric. This condenser is inserted in one branch of the bridge circuit whose other branches contain the variable condenser 13 and the fixed condensers 14 and 15. The junction points between the "actino-dielectric" cell and the condenser 13 and between the fixed condensers 14 and 15, have connected through the means of the terminal 16, a source of radio frequency energy 41. The other junction points of the bridge are connected to the deflection plates 50 17 of a cathode ray tube 19. The cathode ray 55

tube is shown only schematically with its cathode 20 and an apertured diaphragm 21, it being understood, of course, that a suitable electron lens is interposed between the cathode 20 and the deflecting plates 17 to focus the electrons emitted from the cathode 20 into a narrow beam. When the bridge is balanced, i. e. no potential fed to the deflecting plates 17, the cathode ray beam originating at the cathode 20 passes through the aperture in the diaphragm 21. In 5 operation, for example, in a facsimile system, a source of light 30 is focused into a fine spot of light upon a drum 33 by means of an optical system 31. The reflected light is picked up by another optical system 35 and is reflected upon 10 the "actino-dielectric" cell, comprising the two electrodes 11 and 12, and the dielectric layer 10 between them. The bridge is balanced for any 15 predetermined intensity of light falling upon the cell 43 as, for example, for zero illumination. To 20 balance the bridge it is only necessary under these conditions with no light reaching the cell 43, to vary the capacity of the condenser 13 so that no radio frequency potential exists between the two junction points connected to the 25 deflecting plates 17. Under these conditions the cathode ray passes through the aperture of the diaphragm 21. If, however, light is now permitted to fall on the cell 43, the equilibrium of 30 the bridge will be destroyed so that an alternating current potential will appear between the upper and lower junction points of the bridge which, in turn, deflects the cathode ray back and forth across the aperture. The ray, therefore, will move across the diaphragm 21 at the 35 frequency of the alternating current source 41 and with an amplitude depending upon the magnitude of the unbalanced potential difference appearing across the junction points, which are connected to the plates 17.

It will be appreciated that since the frequency is fixed, the amplitude of the swing will determine the duration during which the cathode ray will pass through the aperture in the diaphragm 21, and accordingly, therefore, the number of 45 electrons per unit time which will pass through the aperture will vary in accordance with the intensity of the light upon the cell 43. Beyond the diaphragm 21 may be arranged a suitable 50 secondary emission type of amplifier, or if desired, a single collecting electrode which may be connected to a suitable conventional amplifier for amplifying the cathode ray current received upon the electrode. The output of either of these types of amplifiers may then be used for trans- 55

mission of the electro-optical signal. It will be readily apparent that this type of bridge circuit makes possible the efficacious use of an "actino-dielectric" cell which is both practical, stable and simple.

5 In Figs. 2 and 3 shown, another method by which the "actino-dielectric effect" can be utilized for transmission of electro-optical signals is shown. Fig. 2 shows such an arrangement in perspective.

10 Two electrodes 22 and 23 are arranged parallel to each other and connected through terminals 16 to a source of radio frequency energy 41. The electrode 22 has the surface facing the electrode 15 23 coated with a luminescent material 24. The object to be transmitted is represented by the plane 39 and a suitable optical system 37 projects the object upon the luminescent surface 24 of the electrode 22. A suitable apertured diaphragm 20 45 serves to provide only a single line of the object being projected upon the luminescent surface 24. Suitable means, of course, would be provided in the case of a record larger than a single line for moving either the diaphragm or the object so 25 as to continually scan the subject to be transmitted. Between these two plates a concentrated cathode ray 25 is deflected back and forth and beyond the two plates a narrow apertured diaphragm 47 is provided.

30 It will be immediately appreciated that the cathode ray in passing between the two electrodes 22 and 23 will be deflected, in accordance with the intensity of illumination provided from the exposure of the illumination upon the luminescent 35 material 24. Accordingly, therefore, the number of electrons that pass through the aperture 26 in the diaphragm 47 will be in accordance with the intensity of illumination on the elemental areas of the luminescent material 24. These elemental areas would comprise rectangles of 40 vanishing small widths and whose length is determined by the width of the luminescent material 24. The cathode ray 25 which, in the course of scanning of a line, is moved horizontally past the luminescent layer 24, is thus subjected in its 45 travel to an intensity of a deflecting field, depending upon the intensity of exposure of the respective strip element, and therefore, the ray will be moved to and fro across the aperture 26 with the frequency of the alternating current 50 source 16 in the direction of the arrow P. The electron current passing through the aperture 26 of the diaphragm 47 thus will be varied in accordance with the distribution of brightness 55 along the image light charges projected upon the luminescent layer 24. Beyond the apertured diaphragm 47 a secondary emission amplifier or a collecting electrode with a suitable conventional amplifier connected thereto may be provided as 60 explained above.

65 It will be appreciated, of course, that the showings in both Figs. 2 and 3 are intended merely to represent the disposition of the new electrodes within a cathode ray tube. It will be understood 70 that there is also provided within the cathode ray tube 49 a source of electrons, a suitable electronic lens, and a pair of deflecting plates for causing the ray of electrons 25 to be deflected in the direction at right angles to that shown by the arrow P.

Having described my invention, what I claim as new and desire to secure by Letters Patent is:

75 1. In an electro-optical signaling system, the method of converting varying light intensities representative of an image to be transmitted into

electrical signaling impulses, which comprises the steps of actino-dielectrically producing potential variations in accordance with the varying light intensities, producing a beam of electrons, controlling the produced beam of electrons by the produced potential variations to vary the number of electrons in the beam reaching a predetermined point, collecting the electrons reaching the predetermined point, and producing electrical signaling impulses of an amplitude proportional to the number of collected electrons.

2. In an electro-optical signaling system, the method of converting varying light intensities representative of an image to be transmitted into electrical signaling impulses which comprises the steps of actino-dielectrically producing potential variations in accordance with the varying light intensities, producing a beam of electrons, deflecting the produced beam of electrons by the produced potential variations to vary the number of electrons in the beam reaching a predetermined point, collecting the electrons reaching the predetermined point, and producing electrical signaling impulses of an amplitude proportional to the number of collected electrons.

15 3. An electro-optical signaling system for converting varying light intensities representative of an object to be transmitted which comprises means for actino-dielectrically producing potential variations in accordance with the varying light intensities, means for producing a beam of electrons, means for controlling the produced beam of electrons by the produced potential variations to vary the number of electrons in the beam reaching the predetermined point, means 20 for collecting the electrons reaching the predetermined point, and means for producing electrical signaling impulses of an amplitude proportional to the number of collected electrons.

25 4. An electro-optical signaling system for converting varying light intensities representative of an object to be transmitted which comprises means for actino-dielectrically producing potential variations in accordance with the varying light intensities, means for producing a beam 30 of electrons, means for deflecting the produced beam of electrons by the produced potential variations to vary the number of electrons in the beam reaching a predetermined point, means for collecting the electrons reaching the predetermined point, and means for producing electrical 35 signaling impulses of an amplitude proportional to the number of collected electrons.

40 5. An electro-optical system for converting varying light intensities representative of an object to be transmitted which comprises an electrical bridge having three capacitive arms and an actino-dielectric cell in the fourth arm, means to supply radio frequency energy to one diagonal of the bridge, means to project elemental areas 45 of an image of the object to be transmitted upon the actino-dielectric cell, a cathode ray tube having means to project a beam of electrons along a predetermined path, an apertured diaphragm normal to the predetermined path, a pair of deflecting plates intermediate the means for projecting the beam of electrons and the apertured diaphragm, and connections from the other diagonal 50 of the bridge to the deflecting plates whereby varying light intensities falling on the actino-dielectric cell deflect the beam of electrons to vary the number of electrons passing through the apertured diaphragm.

55 6. An electro-optical system for converting varying light intensities representative of an object to be transmitted which comprises an electrical bridge having three capacitive arms and an actino-dielectric cell in the fourth arm, means to supply radio frequency energy to one diagonal of the bridge, means to project elemental areas 60 of an image of the object to be transmitted upon the actino-dielectric cell, a cathode ray tube having means to project a beam of electrons along a predetermined path, an apertured diaphragm normal to the predetermined path, a pair of deflecting plates intermediate the means for projecting the beam of electrons and the apertured diaphragm, and connections from the other diagonal 65 of the bridge to the deflecting plates whereby varying light intensities falling on the actino-dielectric cell deflect the beam of electrons to vary the number of electrons passing through the apertured diaphragm.

70 7. An electro-optical system for converting varying light intensities representative of an object to be transmitted which comprises an electrical bridge having three capacitive arms and an actino-dielectric cell in the fourth arm, means to supply radio frequency energy to one diagonal of the bridge, means to project elemental areas 75 of an image of the object to be transmitted upon the actino-dielectric cell, a cathode ray tube having means to project a beam of electrons along a predetermined path, an apertured diaphragm normal to the predetermined path, a pair of deflecting plates intermediate the means for projecting the beam of electrons and the apertured diaphragm, and connections from the other diagonal of the bridge to the deflecting plates whereby varying light intensities falling on the actino-dielectric cell deflect the beam of electrons to vary the number of electrons passing through the apertured diaphragm.

object to be transmitted which comprises a cathode ray tube having means to project a beam of electrons along a predetermined path, a deflecting electrode system for deflecting said beam of electrons, said deflecting electrode system comprising a planar metal plate having a coating of actino-dielectric material thereon, said deflecting electrode system being positioned with respect to the path of the electrons with the actino-dielectric material facing the path, an apertured diaphragm positioned beyond the deflecting electrode system, means to supply radio frequency

energy to the deflecting electrode system, and means to project light upon the actino-dielectric material mounted on said planar plate whereby the beam is deflected across the apertured diaphragm.

5

7. A deflecting electrode system for a cathode ray tube comprising a pair of planar parallel plates, and a layer of actino-dielectric material supported upon one of the surfaces of the plates, said surface facing the other of said plates.
